UNITED STATES PATENT OFFICE.

MAX BROCK, OF NEW YORK, N. Y., ASSIGNOR TO I. B. KLEINERT RUBBER COMPANY, OF NEW YORK, N. Y., A CORPORATION OF NEW YORK.

POWDER PUFF.

Application filed January 26, 1923. Serial No. 614,971.

To all whom it may concern:

Be it known that I, MAX BROCK, a citizen of the United States, and a resident of the city, county, and State of New York, have 5 invented a certain new and useful Improvement in Powder Puffs, of which the following is a specification.

This invention relates to an improvement in powder puffs and has for its object to 10 provide an article of this character in which the powder puff will be provided with a plurality of powder applying surfaces enabling two kinds of powder to be applied by the one puff; which will be provided with an 15 improved cover or casing without materially adding to the thickness or bulk of the puff which will keep the powder applying portions or surfaces of the puff clean and sanitary when the article is not being used.

20 With these objects and other objects which may hereinafter appear, in view, I have devised the particular arrangement of parts hereinafter set forth and more particularly pointed out in the claims appended hereto.

25 Reference is to be had to the accompanying drawing forming a part hereof, in which—

Figure 1 is a plan view of the powder puff proper with the casing or cover removed.

30 Figure 2 is an edge view of the same showing one of the powder applying surfaces being spread out flat.

Figure 3 is an edge view of the puff.

Figure 4 is a sectional view on the line 35 4—4 of Figure 1 looking in the direction of the arrows.

Figure 5 is a plan view of the puff, and its cover or casing, parts being broken away to disclose construction.

40 Figure 6 is an edge view of the construction shown in Figure 5, and

Figure 7 is a sectional view on the line 7—7 of Figure 5 looking in the direction of the arrows.

45 Throughout the various views of the drawings, similar reference characters designate similar parts.

The powder puff proper which is disclosed in detail in Figures 1 to 4 inclusive is formed 50 of two outer disks or sections 1 and 2 between which are secured the powder applying sections 3 and 4. These powder applying sections 3 and 4 are normally held in folded position and consist of any suitable 55 absorbent surface such as pile fabric or the

like for receiving and retaining the powder to be applied.

As there are two of these surfaces, it will be seen that two different kinds of powder or rouge may be applied by the one puff. 60 These surfaces or sections of fabric 3 and 4 are secured to the outer edge of the sections 1 and 2 by suitable stitching as at 5.

It will be seen that to use this puff, the section from which the powder is to be removed is spread out flat as indicated in Figure 2.

At 6 are shown stitches which connect the outer sections 1 and 2 together and are located at a point intermediate of the folds 7 70 in the powder applying sections 3 and 4.

The casing or cover for the puff consists of two sections or disks of material shown at 8 and 9 between which the puff is sandwiched and held in such position by stitches 75 10 which extend inwardly from the outer edges of the cover members 8 and 9 and pass through said covers and through the puff which lies between them.

On their inner faces and at their edges, 80 the covers 8 and 9 are provided with interengaging snap fastener members 11 and 12 so that the covers may be detachably engaged together to hold them completely closed about the puff and keep the same 85 clean when it is not in use.

To use the puff, the snap fastener members located at the side from which the powder is to be removed are disengaged from one another and the covers 8 and 9 are 90 spread apart as indicated in dotted lines and the portions of the puff are likewise spread apart so that the powder applying faces form a substantially flat surface from which the powder may be applied. 95

Having described one embodiment of my invention, it is obvious that the same is not to be restricted thereto, but is broad enough to cover all structures coming within the scope of the annexed claims. 100

What I claim is:—

1. An article of the class described comprising a powder puff having a pair of normally folded powder-applying surfaces, flat sections of material independent of said puff being secured on opposite sides of said puff and interengaging, detachable fastening means for uniting the opposite edges of said sections being secured to the sections on their inner faces and adjacent their edges. 105 110 115

2. An article of the class described comprising a powder puff, cover means therefor comprising two flat disks independent of and secured to said puff on opposite sides thereof and means secured to the inner faces of said covers for detachably uniting the edges of said covers at opposite points thereon.
3. An article of the class described comprising a powder puff having a pair of folded powder-applying surfaces, a flat section

of material independent of the puff located on each side of said puff, whereby said puff is sandwiched between said sections, stitching uniting said sections at placed points and extending through the puff, fastener members secured on opposite edges of said sections on their inner faces and adapted to detachably connect said edges. ¹⁵

Signed at the city, county and State of New York, this 8th day of January, 1923.

MAX BROCK.
